SELF-SUSTAINING VISIBLE DISPLAY
MERCANDISE CONTAINER

Joseph L. Rosefield, Alameda, Calif.

Application February 27, 1936, Serial No. 65,961

7 Claims. (Cl. 206—46)

This invention relates to containers which will insure hermetic sealing against evaporation and contamination as well as the advantages of visibility and facility of packaging bestowed upon goods by the use of cellulosic or other like transparent sheet material. The invention has for its object to adapt such transparent sheet material to the production, filling and sealing of containers capable of retaining their own form, lending 10 form or shape to the charge of commodity introduced within them, in some instances serving as the measure of such commodity, and facilitating the embodiment in the container of dispensing facilities in those instances in which controlled or repeated partial discharge of the contained 15 commodity and continued ad interim protection of the undischarged portion are desirable.

Some of the problems incident to the use of transparent sheet material of the class described 20 arise from the difficulty heretofore experienced of fabricating form-retaining containers therefrom; and avoidance of contact with the goods of structural elements pervious and banal thereto.

The present invention proceeds upon the principle of utilizing framing elements constituting a minimum proportion of the confining area of a container, enveloping such framing elements in impervious transparent sheet material, and thereby preventing contact with the goods in instances where such contact would be banal or 25 would leave the goods free to escape by absorption in the framing material; utilizing the frame-enveloping material as a foundation with which to hermetically unite transparent sheet material 30 constituting the remaining confines of the container; co-relating the said remaining transparent confines with the enveloped framing confines in such manner that the frame keeps the transparent confines distended and in a condition to 35 physically restrain the contents of the package; and utilizing a framing confine or confines upon 40 which to mount discharge-controlling, venting or other adjunctive means desirable for particular types of merchandise for the distribution of 45 which the new container may be employed.

In the accompanying drawings, which show several embodiments of the invention by way of illustration—

Figure 1 is a plan view of a framing strip scored 50 to facilitate folding on lines that present its several portions in positions to serve as the four lateral confines of a container frame, together with overlapping frame connections, and having an impervious envelope developed thereon by wrapping it in lap-sealed impervious sheet material 55 of one of the kinds herein contemplated.

Figure 2 is a horizontal section through a framing member developed from the strip shown in Figure 1.

Figure 3 is a section on the line 3x—3x of Fig-

ure 2, and showing the frame open at top and bottom.

Figure 4 is a section on the line 4x—4x of Figure 2, with the addition of a bottom septum or wall of transparent material applied to the framing in accordance with the present invention.

Figure 5 is a view corresponding to Figure 4 and having applied to the top thereof a second septum by way of completing the closure of the container; the filling of the container with a 10 commodity being suggested by cross hatching.

Figure 6 is a vertical longitudinal section of a container developed similarly to Figure 5; the section being taken in a plane which shows, at the left-hand end, the lapped uniting portions of the 15 framing strip, and in the opposite end wall of the frame a grommet, bushing, or the like, constituting a dispensing opening for contained liquid, finely subdivided commodity or other material capable of flowing.

Figure 7 is a section on the line 7x—7x of Figure 6.

Figure 8 is a view corresponding to Figure 1, showing a frame-developing strip enveloped between two substantially co-extensive strips of 25 transparent material laid on opposite sides thereof, with a width permitting the transparent strips to enter into contact beyond the margins of the framing strip and there adhered together to complete the impervious envelope.

Figure 9 is a plan view of a framing blank consisting of material having sufficient rigidity to render it self-sustaining, scored for folding on lines that will develop the bottom and four lateral walls of a tray, and hermetically sealed between 35 two sheets of marginally united impervious material having an area that not only covers the framing material but provides sealing portions to be folded around the four corners of the tray when the said walls are in upstanding position.

Fig. 10 is a view partly in horizontal section, and Figure 11 is a vertical transverse section showing on a larger scale than Figure 9, a fluid tight tray developed from the blank shown in Figure 9.

Figure 12 is a view corresponding to and on substantially the same scale as Figure 9 and smaller than Figure 10, of a blank adapted to be manipulated similarly to Figure 9 into the tray shown in Figure 10, but differing from Figure 9 50 in that the hermetic sealing together of the facing sheets of impervious material is accomplished by folding the margins of a sheet on one side of and of larger area than the framing blank, over the edges of the blank and upon the marginal 55 portions of the sheet on the other side of and substantially corresponding in area to the blank.

Figure 13 is a sectional view of a container made in accordance with the present invention, in principle like the embodiments shown in Fig-

ures 1 to 5, but having a portion of one end of the framing element movable in a manner to adapt the container to serve for dispensing cigarettes and without defeating a desired retention of moisture by the impervious material.

Figure 14 is a vertical section disclosing a tray corresponding generally to the tray shown in Figure 4 but composed of wire framing enveloped in hermetically lap-sealed, impervious sheet material and a bottom closure of the same material.

Figures 15 and 16 are, respectively, a fragmentary vertical section and a fragmentary side elevation of a portion of a container developed in correspondence with that shown in Figure 5, but including venting means to permit escape of interiorly developed gases or pressure of heat-expanded air but checking said vent against ingress of air from the exterior of the package; and

Figure 17 is a view suggestive of the development, under the principle of the present invention, of a hermetic container for the merchandise package of irregularly shaped goods.

Referring to Figures 1 to 3, A represents a strip of pasteboard, cardboard or other material having sufficient rigidity to serve as a collarlike framing for a container, scored at the several points marked X to facilitate its folding on lines developing the two side portions 1 and the two end portions 2 of a rectangular frame, together with a lapping portion 3 for uniting the frame at its fourth corner; and 4 represents a portion of transparent, impervious sheet material enveloping the strip A and hermetically closed around the same by lap-seal 5 existing between the margins 4a and 4b of the said sheet, and lap-seals 6 and 7 just beyond the ends of the strip and in position to fix the assembly of the framing portions by uniting the said end lap-seals upon faces of the enveloping material, as indicated in the assembled frame of Figure 2.

The hermetically enveloped frame as shown in Figures 1 to 3 may be said to provide a tray as shown in Figure 4 where a bottom septum or transparent wall 8 is applied by lapping the margins 9 of a portion of the transparent sheet material upon and adhering them to the outer facings of the frame; or said imperviously enveloped frame may be developed into a hermetic closure surrounding a commodity suggested at Y (Figure 4) by applying both bottom and top transparent sheet closures 8 and 8a, with their margins folded over and permanently united to outer facing materials of the frame members.

As shown in Figures 6 and 7, an end wall of the framing member may serve well for the location of a grommet or other thimble or bushing 10 pressed into gripping relation as shown, with impervious sheets on the inner and outer faces of the end wall 2 around the confines of an aperture in said end wall, and thereby sealing the connection between the wall and grommet. The longitudinal section of Figure 6, being taken in the plane of the dispensing opening 10, shows at its left-hand end the overlap between the parts 2 and 3 of Figures 1 and 2.

As suggested in Figure 8, the frame-forming strip A' may be hermetically enveloped by two strips of impervious sheet material made sufficiently wider than the foldable strip to leave uniting margins of the enveloping material extending beyond the edges of the foldable strip.

Adhesion together of two portions of the enveloping material or transparent wall-forming material may be accomplished by supplying heat to some classes of such material and thereby

fusing together portions thereof which are brought into contact. The same effect may be produced in other classes of such material by the use of a solvent between their meeting faces which causes them to flow together and become united.

In Figure 9, the blank B has its corners cut out as at 11, thereby leaving a portion 12 corresponding to the bottom of a tray, portions 13 corresponding to the sides thereof and portions 14 corresponding to the ends of a tray; and this blank is enveloped in two sheets of impervious material which correspond to and extend substantially beyond the perimeter of the blank, including the cutaway portion 11, to provide for union of the two sheets of enveloping material; and those portions of such enveloping sheets which overlie the corners 11 will, when the end and side walls are folded to an upstanding position, provide uniting laps as suggested on a larger scale, for instance at 11a in Figure 10, and by dotted lines in Figure 11, where, by uniting them with faces of enveloping material which they overlap, the structure of the tray is rendered complete.

Instead of relying on extended margins of the enveloping sheets as in Figure 9, one sheet, as shown in Figure 12, may be cut to closely correspond in area with the foldable framing blank B' plus the corners 11, while the other enveloping sheet is cut sufficiently larger to provide lap-seals 15 folded over the edges of the framing blank and adhered upon marginal portions of the facing sheet first named.

As shown in Figure 13, one end wall 14a of a tray produced as described in connection with Figures 1 to 5, and assumed to have impervious closure sheets stretched over the frame on both of its broad sides, will have a portion 14b of said end member provided with a tongue 14c, as well as a tug 14d so that it may be pulled upward out of the container, for instance, by causing it to bend on the line 14e and thereby develop in the end of the container a sufficient opening for the convenient removal of cigarettes or other commodity packed in the container. Inner and outer impervious facing sheets upon a wall so flexed serve to sustain the wall and maintain the impervious condition thereof.

In Figure 13, the sectionally indicated material 16 is intended to designate the ordinary characteristic proprietary wrapper of the cigarette manufacturer that would be applicable to a container such as shown in Figure 13, 16a being intended to designate, with exaggerated thickness 55 for the sake of clearness, the end folds of such wrapper.

As suggested in Figure 14, a tray or complete hermetic closure embodying the principle of the present invention may be developed by using a wire frame 18 over which is stretched and lap-sealed, as shown at 5a, a sheet of impervious material held distended by said wire frame; supporting the bottom closure 19 lap-sealed at 19a to the sheeting over the lateral confines of said frame; and, if provided at top with a duplication of the closure 19, as in the case of Figure 5, it will constitute a wire-framed hermetic closure.

In Figures 15 and 16 is illustrated a means of interiorly venting and exteriorly checking the container with reference to flow of air or gas, and this means consists of a vent 20 through an end wall 2a terminating, however, beneath the outer facing sheet 21 which overlaps said end wall so that any pressure developing within the

container would pass outwardly between facing sheet 21 and end wall 2a until it reached the slot 22 in said facing sheet offset from said vent 20, where it would become vented to the outside air. 5 A reversal of pressure, however—for instance through means of thermal contraction of air within the container—would not be the means of drawing in air from the outside that might contaminate the goods, but would under excess of 10 external pressure, seal the portion of the outer facing 21 which surrounds the slot 22, against the outer surface of the end wall and thereby prevents air from reaching vent 20.

One advantage of the use of the impervious 15 enveloping material for framed container structures arises from the adaptability of such material to containers of irregular shape where required for special commodities, and Figure 17 illustrates an instance of this kind, 23 being a 20 base and 24, 25 the top and side elements of a framed or form-retaining structure which, being enveloped in the impervious sheeting herein contemplated and having such sheeting properly united at its margins, will constitute the means 25 of extending the principles of the present invention to any shaped form of package that may be desired.

From the foregoing, it will be seen that among the advantages afforded by the present invention are the use of its framing elements for not only lending shape and determining the capacity of the container, but for facilitating the hermetic and, in most instances, integral union between portions of the sheet material that provide the 35 transparent confines of the container and those portions thereof which envelop or overlie the framing elements; the complete envelopment of the framing elements, while an incident to the fullest realization of the advantages of the invention and desirable where contact of the material 40 of the framing elements with the goods would be objectionable because of contamination, absorption or other effect, need only be partial in those instances where hermetic sealing and 45 facility of union of the transparent walls with the shaping walls are the principal desiderata; the enveloping of the framing strip material with the highly flexible hermetic sheet material leaves the enveloped framing strip highly 50 responsive to flexing localized by the scoring or equivalent means in developing any available geometrical form with the shaping element or affording flexibility at point 14e in Figure 13, and in all such situations leaves its angles hermetically 55 protected as well as facilitates hermetic sealing of the meeting ends in closing the selected polygon; and the use of the hermetically united transparent walls throughout their margins to retain the polygonal form of the framing element 60 by its distension over the space defined by the framing element, since distortions of the angles of the polygonal framing element introduce stresses of tension in the transparent wall.

I claim:

1. A container for packaging commodities, said container comprising a framing element defining the perimeter of the package, and a transparent sheet wall closing the space defined by said perimeter; the framing element comprising a flexed strip hermetically enveloped in sheet facing material, the ends of said framing element being lapped in completing the perimeter of the frame, and the hermetic element of the framing en-

velope being extended beyond the lap of said strip and being hermetically sealed upon itself.

2. An impervious merchandising container, comprising a relatively rigid framing member fashioned and flexed to provide an upstanding 5 perimeter for said container with ends that meet to close the same, and impervious facing sheet material overlying said perimeter, extending beyond the ends thereof at the place of meeting and lapped upon and united with the adjacent 10 portion of facing material and thereby hermetically sealing and securing continuity of said perimeter.

3. An impervious container as described in claim 2, in which the framing member includes 15 a portion coincident with a closure in a plane intersecting the perimeter, from which the perimeter-forming portions integrally extend.

4. An impervious container as described in claim 2, in which the framing member includes 20 an area from the edges of which the upstanding perimeter-forming portions integrally extend; said upstanding portions are united by the impervious facing sheet at all of their points of meeting; and the said container includes an 25 impervious sheet closure opposite to the closure provided by the framing member, the last-named closure being marginally lapped upon the upwardly presented edges of the perimeter and hermetically united with the facing sheet thereat.

5. A container as described in claim 2, in which the impervious facing sheet is located on both the outside and the inside of the perimeter, said outside and inside facing sheets being extended past the edges of the perimeter and hermetically 35 united thereat.

6. A container for packaging commodities, said container comprising a relatively rigid framing element covered with inner and outer facings of impervious sheet material, hermetically enclosing 40 said framing element, and a vent for said container comprising a grommet which extends through the framing element and through the facing sheets on opposite sides thereof, said grommet having flanges which overlie the said facing 45 sheets and hermetically exclude the flow of gases or air through the framing element on the outside of the opening of the grommet or between the facing sheets and the grommet.

7. A packaging container comprising a relatively rigid framing element embodied in and defining lateral walls of the container; said walls comprising in addition to said framing element, inner and outer impervious sheet facings united together and hermetically enveloping said walls; 55 said container also comprising flexible sheet confines in planes that include margins of said lateral walls; said sheet confines being hermetically united to sheet facings of the walls and completing the closure of the container; one of 60 said lateral walls being constructed with a gas passage leading from the interior of the container to a point between its outer sheet facing and its framing element and having its said outer sheet facing provided at a point remote from 65 said gas passage, with a free edge past which pressure medium escapes from the container when under a pressure exceeding that of atmosphere, but which checks inflow of air to the gas passage when pressure within the container is 70 below that of atmosphere.

JOSEPH L. ROSEFIELD.
